NONSLIP PARALLEL RULE

Herbert E. Sill, Garden, Mich.

Application June 19, 1946, Serial No. 677,720

1 Claim. (Cl. 33—109)

1 The invention relates to a rule and more especially to a non-slip parallel rule.

The primary object of the invention is the provision of a rule of this character, wherein parallel lines can be scored on a sheet of material, without errors due to the slipping of the rule during the transfer or ruling use thereof.

Another object of the invention is the provision of a rule of this character, wherein it is equipped with rollers, these enabling the movability of the same with ease and dispatch, the rule in its entirety being of novel construction and is unique in the assembly of its parts, which are comparatively few in number, thus economical to repair and replace.

A further object of the invention is the provision of a rule of this character, which is simple in construction, thoroughly reliable and efficient in operation, strong, durable, compact, readily and easily operated, useful to navigators, draftsmen or other craftsmen and inexpensive to manufacture.

With these and other objects in view the invention consists in the features of construction, combination and arrangement of parts as will be hereinafter more fully described, illustrated in the accompanying drawings, which disclose the preferred embodiment of the invention, and pointed out in the claim hereunto appended.

In the accompanying drawings:

Figure 1 is a side view partly broken away of the rule constructed in accordance with the invention.

Figure 2 is a fragmentary view similar to Figure 1 showing an adjustment of the rule.

Figure 3 is a top plan view of the rule with cover removed.

Figure 4 is an end view.

Figure 5 is a sectional view taken in the line 5—5 of Figure 3 looking in the direction of the arrows.

Figure 6 is a plan view of a pair of the rollers longitudinally disposed in the rule.

Figure 7 is a fragmentary detail sectional view through one of the roller mountings.

Figure 8 is a side view thereof.

Figure 9 is a top plan view of a guide plate.

Figure 10 is an edge view of the guide plate.

Figure 11 is a fragmentary side view partly broken away, of one of the adjustable mountings for the end roller.

Similar reference characters indicate corresponding parts throughout the several views in the drawings.

Referring to the drawings in detail, the rule

constituting the present invention, comprises a substantially rectangular shaped or elongated body 10, having a flat bottom face 11, while at opposite longer side edges are beveled straight line ruling flanges 12 which are co-extensive with the longitudinal extent of the body 10 for parallel ruling purposes.

Capping the top of the body 10 is a crown housing 13, so conformed as to provide a hand grip, 10 while counterseated within the bottom face of the said body 10 in a longitudinal direction thereof are spaced parallel roller axles 14 carrying rollers 15, which protrude beyond the face 11 to have contact with a paper sheet supported on a level bed or on a table top, not shown, so that the body 10 can be rolled broadside in reverse directions. The axles 14 are journaled in block bearings 16 adjustably suspended by screws 16^a from brackets 16^b secured within the body. The brackets 16^b are provided with vertical slots 16^c for the reception of the ends of the axles 14. These rollers 15 are what might be termed side rollers.

Near opposite ends of the body 10 and movable 25 vertically in suitable openings 17 provided therein, are cross and axles 18 for divided end rollers 19, each axle 18 being journaled in vertically adjustable block bearings 20, which are spaced apart and slidably fitted in guide sleeves 21 depending from closure plates 22 overlying the openings 17 for each divided end rollers 19, and made fast to the top 23 of the body 10 as best seen in Figure 5 29 of the drawings. The ends of the axles 18 are loosely mounted in vertical grooves 18^a in the end walls of the openings 17.

At the longitudinal and transverse center axis of the body 10 and the crown housing 13 is an upwardly tapered column 24 which is confined 27 within such housing and within which is workable a vertically slidable plunger 25, while in the upper stem portion 26 is adjustably connected a presser head 27, the crown housing being cleared 01 for the stem 28, as at 29. This plunger 25 is tensioned by a coiled spring 30 set over a guide pin 30^a between it and the body 10. The guide pin 30^a is fixed to the body 10 and has a loose fit in a bore 25^a in the plunger 25. Slidably mounted in guides 31 fixed to the top of the body 10 are actuator bars 32, which extend in reverse directions to each other longitudinally of the body at its longer center medium. Links 33 pivotally connect the inner ends of the bars 32 to the plunger 25, as at 35. The outer end of each bar 32 has sloping slots 36, in which the ends of a rod 36 are mounted. The bearing blocks 20 are

suspended from the rods 36^a by set screws 37^b and blocks 37^a which provide for the vertical adjustment of the bearing blocks with relation to the rods. The spring 30 and springs 37 associated with the body 10 and bars 32, function to hold the end rollers 19 with portions of their peripheries below the lower surface of the body 10 and below the plane in which the lower sides of the side rollers 15 are located, whereby normally to support the body 10 on the end rollers, and thus provide for the endwise movement of the device. To retract the end rollers 19, whereby to effect the supporting of the device on the side rollers, and thus provide for its sidewise movement, the presser bar 27 is depressed.

The screws 37^b are engaged with the upper ends of the bearing blocks 20 and swivelly connected to the blocks 37^a, the latter being mounted on the rods 36^a.

At each end and each opposite side of the body 10 are the spirit levels 38 and 39 respectively so that it can be determined when the rule is resting at a level in the longitudinal and transverse directions.

The rollers 15 and 19 when in contact with a surface prevent the slipping of the rule and in this way no errors therefrom can come about in ruling parallel lines, the rule being rolled broadside or endwise in contradistinction to the sliding thereof upon a surface, during the use of the said rule.

What is claimed is:

A non-slip parallel rule, comprising a boardlike body, a crown-shaped housing upon the body, relatively spaced fixed journals in said body, four longitudinally extending rollers having axles mounted in said journals so that said rollers ex-

tend a predetermined distance below the bottom surface of said body, said rollers being journaled in pairs in said body with each longitudinally extending pair adjacent the sides thereof and the outer ends of the rollers inwardly of the outer ends of the body and said rollers are adapted to permit transverse movement of the body, and rollers mounted in said body adjacent the outer ends thereof outwardly of the outer ends of said first rollers to permit longitudinal movement of the body, journals for the end rollers, said journals being adjustable to raise or lower said end rollers with relation to the plane of contact of said first rollers so that the contact of said first rollers with a surface may be varied, means for simultaneously moving the end rollers to simultaneously lift said first said rollers from contact with said surface so that all of said first rollers are moved into contact or out of contact with the surface in one movement of said means, said means comprising a pair of bars each including an inclined surface at one end engaging a portion of each of said adjustable journals, and a plunger operably connected to said bars at the ends opposite to said inclined surface, and means for holding the end rollers inactive.
